(57) **CLAIM**

The ornamental design for a surgical suction instrument, as shown and described.

DESCRIPTION

FIG. 1 is a top perspective view of a surgical suction instrument showing our new design;

FIG. 2 is a bottom perspective view thereof;

FIG. 3 is a front view thereof;

FIG. 4 is a top plan view thereof;

FIG. 5 is a rear view thereof;

FIG. 6 is a right side view thereof;

FIG. 7 is a bottom plan view thereof;

FIG. 8 is a left side view thereof;

FIG. 9 is a top perspective view thereof, with the suction tip removed for ease of illustration;

FIG. 10 is a bottom perspective view thereof;

FIG. 11 is a front view thereof;

FIG. 12 is a left side view thereof;

FIG. 13 is a top plan view thereof;

FIG. 14 is a rear view thereof;

FIG. 15 is a right side view thereof; and,

FIG. 16 is a bottom plan view thereof.
